VALENTIN LORENTZ, OF DRESDEN, GERMANY, ASSIGNOR TO UNITED CIGARETTE MACHINE COMPANY AKTIENGESELLSCHAFT, OF DRESDEN, GERMANY

METHOD OF AND APPARATUS FOR LOOSENING TOBACCO PARTICLES AND FREEING THEM FROM DUST

Application filed April 28, 1928, Serial No. 273,642, and in Germany March 19, 1927.

This invention relates to a process and an apparatus for loosening and freeing tobacco from dust designed and adapted for use with pneumatic conveyances.

6 The pneumatic conveyance of cut tobacco to the various points where it is cleaned, loosened or otherwise treated is already known.

10 The pipes through which the tobacco is conveyed from the cutting machine are generally of cylindrical section. It has already been proposed to curve them strongly, as well as to provide them with abutment members, in order to loosen the tobacco particles and to separate more thoroughly the dust from the 15 tobacco, in that this latter is then caused by the air current to push upon the pipe walls or upon the abutment members. Hereby, however, the tobacco particles may be damaged or pulverized unintentionally.

20 The present invention relates to an improved method and means for freeing the tobacco from dust in its passage through the feed tube.

25 In the process, according to the present invention, the air, which carries the tobacco with it, is given alternately higher and lower rates of speed. The result of this is that the tobacco advances more quickly at the places where the air speed is greater, whereby it is separated and the dust set free, and at those points, at which the speed of the air current is reduced, the tobacco is turned and whirled about by the whirling movement of the air, and completely freed from dust.

30 The varying speed of the air current as it carries the tobacco along with it may be obtained by many different means, for instance, the speed of the air current can be increased by the use of fans or by the influx of compressed air or air may be drawn in at certain places in the tube and by other similar means. Preferably, the varying speed of the air current is obtained by widening and constricting parts of the feed tube.

35 A particularly effective configuration of a pipe for the purpose in question is illustrated in the figure. The free sectional area of this pipe is different at different parts, in consequence whereof the velocity of the air varies accordingly. The effect thereof is that the

tobacco passing through the smaller free sectional areas is drawn asunder so as to expose the dust to the air, whereas in the larger free sectional areas the eddies there forming cause the tobacco particles to whirl through 55 one another whereby the particles are loosened and dust is completely removed from the same and carried away. The drawing shows a side view of a pipe through which the cut tobacco is conveyed, for instance, from the 60 cutting machine to a cigarette making machine. This tube has narrow portions 106, 107 where the speed of the air is by far higher than in the wider portions 108 and 109. The tobacco is drawn asunder in the narrow 65 sectional areas and whirled through in the larger ones. The arrows indicate the direction in which the air is streaming through that tube. I wish it to be understood that the drawing shows merely an example. Many 70 other configurations of the tube or of an equivalent conduit for it are possible, and also equivalent means may be used for the particular purpose intended.

I claim:—

75 1. A method of loosening tobacco particles and freeing same from dust consisting in conveying the tobacco particles by means of an air stream having different speeds in different parts of its path.

80 2. A device for pneumatically separating adhering tobacco particles and dust which consists exclusively of a tube of a configuration having alternate narrow and wide portions to thereby vary the speed of the air in 85 the tube.

In testimony whereof I affix my signature.

VALENTIN LORENTZ.
